UNITED STATES PATENT OFFICE.

PASCAL J. SHAMPAY, OF CHICAGO, ILLINOIS.

DRYING MACHINE.

Application filed March 18, 1920, Serial No. 366,928. Renewed February 27, 1922. Serial No. 539,750.

To all whom it may concern:

Be it known that I, PASCAL J. SHAMPAY, a citizen of the United States, residing at Chicago, in the county of Cook and State of Illinois, have invented certain new and useful Improvements in Drying Machines, of which the following is a specification.

My invention relates to drying machines, and has for one of its objects the provision 10 of simple and efficient means for holding articles to be dried in tubular form.

A further object is the provision of simple and efficient means for holding an article in tubular form and circulating the air in said 15 tubular article.

A still further object is the provision of means for holding an article to be dried in tubular form with means for closing the 20 ends of the tubular article and admitting heat to the interior of said tubular article.

A still further object is the provision of means for holding an article in tubular form with said means arranged to hold the article stretched taut longitudinally of the tubular 25 article.

Other objects will appear hereinafter.

An embodiment of my invention is indicated in the accompanying drawings forming a part of this specification, and in which, 30 Fig. 1 shows a plurality of drying machines attached together and embodying my invention.

Fig. 2 is a section taken on line 2—2 of Fig. 1.

Fig. 3 is a vertical fragmental section taken through one of the drying elements shown in Fig. 1.

Fig. 4 is a view taken on line 4—4 of Fig. 3, and

Fig. 5 is an enlarged fragmental view of the base portion of my drying device.

Referring more particularly to the drawings, I have indicated a horizontal steam pipe 6 having a plurality of fittings 7 there- 45 in. The number of fittings 7 used in any set of devices corresponds to the number of drying elements to be installed. One fitting 7 is necessary for each drying element. A frame 8 is also provided above the pipe 6 for partially supporting the drying ele- 50 ments. This frame may be made of angle iron, as shown, or of any other desirable materials.

In each fitting 7 I preferably provide a valve 9 for controlling the passage of steam or other heating fluid from pipe 6 into a dry-

ing element. The fitting 7 is preferably angular with a vertical portion in which is threaded, or otherwise attached, a substantially vertical heater 10. In the present instance, I have shown the vertical heater 10 as being made up of a large pipe 11 and a smaller pipe 12 connected together by a reduced coupling 13 and a cap 14 at the top of pipe 12. It will be understood that the heater may be made of any desirable materials. I also preferably provide a vent valve 15 at the top of the heater so as to maintain live steam in said heater.

Disposed on the frame 8 I provide a disc 16 providing a bottom closure for the drying chamber. This disc 16 is preferably provided with an opening 17 at its center through which the pipe 11 passes.

At the upper end of the heater I provide a disc 18 having a hub 19 which is slidably mounted on the pipe 12. The cap 14 provides a stop limiting the upward movement of hub 19 on said pipe 12. On the under side of disc 18 and around the pipe 12 I provide a spring 20 which presses upwardly on said disc 18. At the lower end of the spring 20 I provide a mounting 21 having a set screw 22 therein. The arrangement of mounting 21 is such that by loosening set screw 22 more or less tension can be placed on spring 20. Also, when it is desired to dry articles of different lengths or widths, the mounting 21 can be adjusted along on pipe 12 to accommodate these different widths or lengths. The mounting 21 may be formed in any desirable manner, that indicated being formed of slidable members 23

on pipe 12 with bars 24 reaching up to a disc 25 which supports the spring 20.

Journalized on the pipe 11 I have mounted a fan made up of spiders 26 and blades 27. Depending from the lower spider 26 is a hub member 28 extending down through openings 17 in disc 16 with a bevel gear 29 attached thereto. The bevel gear 29 meshes with a bevel gear 30 which is fixed on a shaft 31 mounted in a suitable part of fitting 7.

On the shaft 31 I provide a pulley 32 for operating shaft 31. When a number of the drying elements are placed along in a line as indicated in Fig. 1, one belt, not shown, may be passed around the pulleys 32 to effect simultaneous rotation of the fans or

these fans may be driven in any other desirable manner. Between the upper end of fitting 7 and the lower side of gear 29 I

provide an anti-friction bearing 33. This bearing in the present instance is indicated as a ball thrust bearing. It will be apparent that any other form of anti-friction bearing 5 may be used.

On the periphery of disc 16 I provide a flange 34 which is provided with one or 10 more tongues 35 extending inwardly toward the axis of the disc 16. At another portion 15 of the flange 34 I provide a spring-pressed dog 36. The tongues 35 and dog 36 are adapted to lock the means for holding the article to be dried.

I have indicated the means for holding 20 the article to be dried as being made up of two annular members, one adapted to engage disc 16 and the other the disc 18 while an article is being dried. Each of the annular members is made up of a ring 37 which may be of angular construction such as a Z-shaped bar, as shown. One portion 25 of the bar 37 has perforations or notches 38 therein to permit the water to flow out of the article being dried around onto disc 16. Each of the rings 37 is provided with a 30 number of points 39 upon which the article to be dried is placed. The article to be dried may be wound around on the rings 37 and points 39 in any desirable manner and the articles to be dried may be wound in one or 35 more turns, as desired.

To hold the article to be dried on points 39, I have indicated rings 40 which may be secured to the rings 37 by screws 41 or their 40 equivalent.

The ring 40 adjacent disc 16 is provided with a groove 42 which engages the tongues 35 and spring-pressed dog 36 to hold the 45 ring 37 against disc 16. The upper ring 37 is provided with a ledge 43 adapted to rest on the top of disc 18, the arrangement being such that when the article to be dried is placed on points 39 and lower ring 40 is locked against disc 16, spring 20 will 50 press disc 18 up against ledge 43 to hold the article to be dried, that.

This drying device is particularly adapted for drying bed blankets and the like, but it will be apparent that many other articles 55 may be dried also on the device by making the latter in proper sizes.

I claim:

1. A drying machine comprising an upright heating element; a fan mounted on 55 and adapted to revolve around the heating element; and an annular non-rotary means for holding an article to be dried in tubular form around the fan.

2. A drying machine comprising a substantially vertical steam pipe; a fan journaled on the steam pipe and adapted to rotate around the latter; an annular blanket support around the lower portion of the steam pipe; and an annular blanket support 60 at the upper portion of the steam pipe, the

annular blanket supports being disposed in substantially horizontal planes and of a size larger than the periphery of the fan.

3. A drying machine comprising a substantially vertical steam pipe; a fitting at 70 the bottom of and supporting said steam pipe; a fan journaled on said steam pipe; an anti-friction bearing between and supporting said fan on said fitting; power means connected with the fan; and a blanket-holder adapted to hold a blanket in tubular form around the fan.

4. A drying machine comprising a vertical heater; a fan journaled around the heater; a horizontal disc-shaped member below the 80 fan; a disc-shaped member at the top of the fan; and means at the peripheries of said disc members for holding a blanket in tubular form so that the blanket and said disc members entirely enclose the fan.

5. A drying machine comprising a substantially vertical heater; a fan journaled around the heater; a horizontal disc-shaped member below the fan; a disc-shaped member 85 slidably mounted on said heater; a spring-pressing upwardly on the disc at the upper portion of said heater; and means at the peripheries of the disc members for holding a blanket in tubular form around said fan.

6. A drying machine comprising a substantially vertical heater; a fan journaled around the heater; a horizontal disc-shaped member below the fan; a disc-shaped member 90 slidably mounted on the heater and sub- 95

stantially parallel with the first mentioned disc member; a spring spreading upwardly on the disc member at the upper portion of the heater; a stop on the heater limiting the upward movement of said disc member at 100 105

the heater; a step on the heater limiting the upward movement of said disc member; and means for securing a blanket around the peripheries of the disc members.

7. A drying machine comprising a substantially vertical steam pipe; a stop at the top of the steam pipe; a horizontal disc 110 slidably mounted on the steam pipe; a spring having one end adjustably secured on the steam pipe and the other end 115 operatively associated with said disc; a disc having a central perforation with the steam pipe extending through said perforation; a fan on the pipe with its hub extending out through said perforation; driving means attached to said hub; and blanket holding rings engaging the edge of said disc.

8. A drying machine comprising a plurality of spaced disc members; means at the peripheries of the disc members adapted to hold an article to be dried in tubular form; 120 and a fan rotatably mounted between the disc members.

9. A drying machine comprising a heating element; a fan rotatably mounted around the heating element; a stationary disc at the 125 130

- lower end of the fan; a disc slidably mounted above said fan; resilient means pressing upwardly on the slidably mounted disc; and an article to be dried holding ring 5 at the periphery of each of said discs, the upper ring resting on the slidably mounted disc and the lower ring being removably locked to the lower disc.
10. A drying machine comprising an up-right heating element; a fan rotatably mounted on the heating element; a stationary disc on the heating element at the lower end of the fan; a disc slidably mounted on the heating element above the 15 fan; resilient means pressing upwardly on the slidably mounted disc; a ring having a portion resting on the peripheral edge of the slidably mounted disc, a ring resting on the disc at the lower end of the fan; a flange 20 on the last-mentioned disc; locking means locking the last-mentioned ring to said flange; and article to be dried holding points on said rings.
11. A drying machine comprising an up-right steam pipe; spaced-apart rings substantially concentric with said steam pipe 25
- means on said rings for supporting articles to be dried; and means for moving air from the steam pipe radially from the latter.
12. A drying machine comprising an up-right steam pipe; means for holding articles to be dried in tubular form around said steam pipe; and means for moving air from said steam pipe toward articles to be dried. 30
13. A drying machine comprising two spaced blanket holding members adapted to hold a blanket in tubular form; a fan within said blanket holding members; and means for feeding hot air to said fan. 35
14. A drying machine comprising two disc-shaped members having blanket holding devices at their peripheries; a mounting for one of said discs holding the latter stationary; a mounting for the other disc holding the latter resiliently; means for introducing hot air to the space between said discs; and means for forcing said air radially from the axis of said discs. 40
- 45

In testimony whereof I have signed my name to this specification on this 11th day of 50 March A. D. 1920.

PASCAL J. SHAMPAY.
